JOHN E. SAUNDERS, OF EDGEWOOD BOROUGH, PENNSYLVANIA, ASSIGNOR TO THE UNION SWITCH & SIGNAL COMPANY, OF SWISSVALE, PENNSYLVANIA, A CORPORATION OF PENNSYLVANIA.

INDICATION APPARATUS FOR RAILWAY-TRAFFIC-CONTROLLING APPARATUS.

1,257,743.

Specification of Letters Patent. Patented Feb. 26, 1918.

Application filed July 12, 1917. Serial No. 180,081.

To all whom it may concern:

Be it known that I, JOHN E. SAUNDERS, a citizen of the United States, residing at Edgewood borough, in the county of Allegheny and State of Pennsylvania, have invented certain new and useful Improvements in Indication Apparatus for Railway-Traffic-Controlling Apparatus, of which the following is a specification.

10 My invention relates to railway traffic controlling apparatus, and particularly to indication apparatus for railway signals.

I will describe one form of apparatus embodying my invention and will then point 15 out the novel features thereof in claims.

The accompanying drawing is a diagrammatical view showing a railway track, two signals, controlling means for said signals, and one form of indication apparatus for 20 said signals embodying my invention.

Referring to the drawing in detail, the reference character T designates a stretch of railway track, from which traffic may be diverted by a switch A. For governing traffic in either direction on the main track through the switch A, I provide two signals S and S', which are located upon opposite sides of the switch, as shown. These signals S and S' are, as here shown, of the 30 semaphore type, each being capable of giving two indications, viz., "stop" and "proceed", according as the semaphore is in the horizontal or the inclined position. Each signal is biased to the stop position, and may 35 be moved to the proceed position by virtue of current from a source B, through the medium of a suitable signal operating mechanism which is not shown. The control circuits for the signals are shown in dot-and-

40 dash lines, to distinguish them from the circuits for the indication apparatus which latter are shown in solid lines. These signal control circuits are governed by a circuit controlling lever C, which lever is usually 45 one of a plurality of similar levers comprised in an "interlocking machine". As here shown, the lever C comprises a shaft 14 which is adapted to rock and which operates a contact finger 15 for the control of the 50 signals. In the arrangement of the control circuits here shown, one or the other of the signals S or S' is connected with the source of current B, and so is moved to the

proceed position, according as contact finger 15 engages contact 16 or 17, that is, according as lever C is swung in one direction or the other from its middle position. 55

Although I have shown only two signals controlled by the lever C, it is to be understood that any number of signals may be 60 used and controlled by the lever, without departing from the spirit and scope of my invention.

Movements of the shaft 14 are as usual controlled by a locking or indication device 65 E, which, as here shown, comprises a segment 18 fixed to the shaft 14 and provided with a dog 19 which coacts with a latch 20. This latch is biased to engage with the dog, but may be raised out of the path thereof 70 by an indication magnet M. The indication magnet M is provided with a circuit which is controlled by an electromagnetic device D responsive to reversals of current. The circuit for the indication magnet is also controlled by a contact finger 21 operated by the lever C, such finger being adapted to engage either of a pair of segmental contacts 22 or 23 according as the lever is swung 75 in one direction or the other from its middle position.

The electromagnetic device D, in the form here shown, is a relay comprising two contact fingers 24 and 25. Contact finger 24 is actuated by a neutral armature, that is, 85 it is responsive to the presence or absence of current in the relay, while contact finger 25 is actuated by a polarized armature, so that it engages with a fixed contact 38 or another fixed contact 49 according as current flows 90 through the coils of relay D in one direction or the other.

The circuit for the indication magnet M is from battery B through wires 32 and 39, contact 24, contact 25-38, wire 40, magnet 95 M, wire 41, contact 22-21, or 23-21, wire 42 to battery B. Consequently, magnet M is energized only when relay D is energized in such direction as to close contact 25-38, and lever C is swung in one direction or the 100 other from its middle position.

Relay D is provided with a circuit which is controlled by two pole-changing circuit controllers P and P', operated by signals S and S' respectively. Circuit controller P, 105 which is directly connected to and operated

by signal S, comprises two movable contact fingers 26 and 27, while circuit controller P', which is directly connected to and operated by signals S', comprises four movable contact fingers 28, 29, 30 and 31. These circuit controllers and the connections thereto are so arranged that when both signals are in the stop position, relay D is energized by current from battery B in such direction that the polarized contact 25-38 is closed, and that when either signal is in the proceed position, relay D is energized in the opposite direction so that the polarized contact 25-49 is closed. When either or both signals occupy a position intermediate the stop and proceed positions, relay D is disconnected from source B so that neutral contact 24 of relay D will be open, thereby preventing energization of indication magnet M. Similarly, relay D is deenergized when both signals indicates "proceed" simultaneously. This is due to the fact that when signals S and S' are in the proceed positions, terminal 37 of battery B is connected to wire 48 by contact finger 27, but contact finger 28 is disconnected from wire 44 so that the circuit for the relay D is disrupted.

L designates an incandescent lamp for giving a visual indication when signal S or S' is in the "proceed" position. Lamp L is provided with a circuit which is controlled by contact 25 of relay D. This circuit is as follows: from battery B, through wires 32 and 39, contact 24, contact 25-49, wire 50, lamp L, and wires 51, 42 and 37 back to battery B. Another type of indicating device may be substituted for lamp L.

The signaling and indication apparatus here shown are usually employed in conjunction with railway switch operating mechanisms, such mechanisms being controlled by levers similar to lever C and forming part of an "interlocking machine."

The operation of the entire apparatus is as follows: lever C is shown in its middle position, wherein contact fingers 15 and 21 are disengaged from their respective cooperating fixed contact members. Consequently, signals S and S' both indicate stop, and the circuit for indication magnet M is open. Relay D is now energized by current flowing from battery B through wire 32, contact finger 26, wire 33, contact finger 31, wire 34, relay D, wire 35, contact finger 29, wire 36, contact finger 27, and wire 37 back to source B. The current thus flowing in relay D is in such direction that contact 25-38 is closed and contact 25-49 is open.

When it is desired to move signal S' to the proceed position, lever C is swung to the left, whereupon contact 15-17 is closed, thereby closing the circuit for signal S' so that such signal moves to the proceed position. The circuit for signal S' is thought to

be obvious; therefore the same will not be traced in detail. Simultaneously with the movement of signal S' to the "proceed" position, circuit controller P' is moved to the position shown in dotted lines, thereby completing the following circuit: from battery B through wire 32, contact finger 26, wire 33, contact finger 31, wires 43 and 35, relay D, wires 34, 44 and 45, contact finger 29, wire 36, contact finger 27, and wire 37, back to battery B. Relay D is now energized in such direction that contact 25-38 is opened, thus disrupting the circuit for indication magnet M so that the latter is deenergized, causing latch 20 to drop to its biased position beyond the end of dog 19 and so locking the lever in substantially its full stroke position. Contact 25-49 is now closed, thus completing the circuit for lamp L which then gives a visual indication that one of the signals is in the proceed position. A slight movement of the lever C toward middle position is permitted, however, to allow the contact finger 15 to disengage from contact 17, thereby disrupting the circuit for signal S' and so causing this signal to return to its stop position. Circuit controller P' is thus returned to the position in which it is shown in solid lines, so that relay D is again energized in such direction that contact 25-38 is closed, and contact 25-49 is opened, thereby energizing indication magnet M, causing latch 20 to be lifted out of engagement with dog 19, thus permitting lever C to be fully returned to the middle position. When the lever is returned to the latter position, magnet M is deenergized because of its circuit being disrupted by the opening of contacts 21-22.

The operation of the apparatus when moving signal S from stop to proceed positions and vice versa is identical to that just described for signal S', except that lever C is rotated to the right from its middle position. Contacts 16 and 23 now perform the same functions as contacts 17 and 22. When signal S is in the proceed position relay D is energized by the following circuit: from battery B, through wire 32, contact finger 26, wire 46, contact finger 30, wires 47 and 35, relay D, wires 34 and 44, contact finger 28, wire 48, contact finger 27, and wire 37 back to battery B. Relay D is then energized in such direction that contact 25-38 is open and contact 25-49 is closed.

It will be seen from the foregoing that the pole-changing contacts P and P' and their connections are so arranged that when both signals S and S' are in stop position, relay D is energized in the proper direction to close contact 25-38, but that when either signal is in the proceed position this relay is energized in the opposite direction so that contact 25-38 is open and the indication magnet M cannot be energized. Both sig-

nals in the clear position (an abnormal condition) would cause relay D to be deenergized and neutral contact 24 to be open.

Although I have herein shown and described only one form of apparatus embodying my invention, it is understood that various changes and modifications may be made therein within the scope of the appended claims without departing from the spirit and scope of my invention.

Having thus described my invention, what I claim is:

1. In combination, two signals, an electromagnetic device responsive to reversals of current, contacts and connections controlled by said signals for energizing said device in one direction when both signals indicate stop and in the reverse direction when either signal indicates proceed, and indication means controlled by said electromagnetic device.

2. In combination, a plurality of signals, an electromagnetic device responsive to reversals of current, contacts and connections controlled by said signals for energizing said device in one direction when all of said signals indicate stop, in the reverse direction when any one signal indicates proceed, and for deenergizing said device when any two or more signals indicate proceed simultaneously, and indication means controlled by said electromagnetic device.

3. In combination, two signals each biased to stop position, a controlling lever having a middle position and capable of movement in opposite directions therefrom, means controlled by said lever for moving one signal or the other to the proceed position according as said lever is moved in one direction or the other from said middle position, electromagnetic means responsive to reversals of current, contacts and connections controlled by said signals for energizing said electromagnetic means in one direction when both signals indicate stop and in the reverse direction when either signal indicates proceed, and a locking device controlled by said electromagnetic means for preventing return of said lever to its middle position except when said electromagnetic means is energized in the first-mentioned direction.

4. In combination, two signals S and S', an electromagnetic device D responsive to reversals of current, a source of current, two pairs of wires 33, 36, and 46, 48 extending between said signals, contacts controlled by one of said signals for connecting the termi-

nals of said source with wires 33 and 36, or with wires 46 and 48 according as the signal indicates stop or proceed, contacts controlled by the other signal for reversibly connecting the electromagnetic device D with wires 33 and 36 according as the signal indicates stop or proceed and for connecting said device D with the wires 46 and 48 when the signal indicates stop, said connections being so arranged that the device D is energized in one direction when both signals indicate stop and in the other direction when either signal indicates proceed, and indication means controlled by said device D.

5. In combination, two signals, an electromagnetic device responsive to reversals of current, contacts and connections controlled by said signals for energizing said device in one direction when both signals indicate stop and in the reverse direction when either signal indicates proceed, and means controlled by said device when energized in the last-mentioned direction for indicating that one of said signals indicates proceed.

6. In combination, two signals, a controlling lever for said signals, an electromagnetic device responsive to reversals of current, contacts and connections controlled by said signals for energizing said device in one direction when both signals indicate stop and in the reverse direction when either signal indicates proceed, locking means for said lever controlled by said device and rendered effective to release the lever when the device is energized in the first-mentioned direction, and means controlled by said device when energized in the other or reverse direction for indicating that one of said signals indicates proceed.

7. In combination, two signals, a controlling lever for said signals, an electromagnetic device responsive to reversals of current, contacts and connections controlled by said signals for energizing said device in one direction when both signals indicate stop and in the reverse direction when either signal indicates proceed, and locking means for said lever controlled by said device and rendered effective to release the lever when the device is energized in the first-mentioned direction.

In testimony whereof I affix my signature in presence of two witnesses.

JOHN E. SAUNDERS.
